UNITED STATES PATENT OFFICE.

JAMES HENRY COTTON, OF TORONTO, ONTARIO, CANADA, ASSIGNOR TO E. I. DU PONT DE NEMOURS & COMPANY, OF WILMINGTON, DELAWARE, A CORPORATION OF DELAWARE.

ANÆSTHETIC.

No Drawing.

Application filed September 25, 1918. Serial No. 255,636.

To all whom it may concern:

Be it known that I, JAMES H. COTTON, of Toronto, in the Province of Ontario, Canada, have invented a certain new and useful Improvement in Anæsthetics, and do hereby declare that the following is a full, clear, and exact description thereof.

My invention relates to anæsthetics and pertains especially to such compositions as contain, as an essential constituent, what I have designated an anæsthetic gas.

The administration of ether-anæsthetics, as is well known, is often inadvisable, or regarded by the patient with aversion, because of the physiological effects produced thereby, such as irritation of the mucous membranes, and after-sickness or nausea.

One object of my invention is to provide an inhalation anæsthetic, and particularly one comprising an ether (preferably ethyl ether), which will not cause the above mentioned undesirable physiological reactions, and which has a much greater anæsthetic power than ordinary ether, so that the amount administered for a given degree of anæsthesia may be much less than is required when using ordinary ether.

Other objects of my invention will be apparent from the following description.

I have discovered that certain gases, such as the gaseous olefine, ethylene (C_2H_4), and carbon dioxide (CO_2), possess remarkable anæsthetic properties, when associated with a highly volatile narcotic such as an alkyl ether, and that the administration of a gaseous mixture containing substantially pure ether and a small proportion of ethylene or carbon dioxide, or both, is not attended by irritation of the mucous membrane and does not cause after-sickness. Furthermore the ease of induction of the new anæsthetic is much greater than that of ordinary ether; and the prompt recovery from its effects, with no disagreeable after features, is very noticeable.

I have also discovered that these anæsthetic gases (ethylene, carbon dioxide, etc.) in conjunction with ether are able to produce analgesia (loss of sensation and peripheral vaso-motor spasm) without at the same time producing complete anæsthesia. In other words, the patient may be rendered insensible to pain, and yet retain conscious-

ness; he can carry on a conversation intelligently, and even walk about, although rather unsteadily. If the amount administered is reduced sensation begins to return; while if it is pushed, the condition passes over into ordinary surgical anæsthesia, with loss of consciousness but with a markedly lessened interval of excitement. This analgesic condition seems to be very similar to the "primary anæsthesia" obtainable with ordinary ether, with the difference that while primary anæsthesia is very brief, the analgesia producible by the new anæsthetic can be extended several hours if need be.

In order to produce the new anæsthetic I add to a good grade of ethyl ether a definite proportion of an anæsthetic gas or gases such as ethylene and carbon dioxide. I have found that good results are obtained by the addition of approximately the amount of ethylene and carbon dioxide which will be retained by ether at normal temperatures and at atmospheric pressure, i. e., about two volumes of these gases to one volume of liquid ether. I have found that it is possible to add more ethylene and carbon dioxide to the ether by cooling the ether while the gases are being added and subsequently keeping the ether in a closed container to prevent the escape of the anæsthetic gases. For most purposes the best results are obtained by the addition of an amount of the anæsthetic gases ranging from an equal volume to five or six times the volume of the liquid ether, so that the resulting ether contains from about .15% to 1% by weight of absorbed gases.

As an example of an efficient anæsthesia ether I may mention that excellent results are obtained with pure ether to which there has been added an amount of pure ethylene equal to twice the volume of the ether. Excellent results have also been obtained with ether to which 3.5 volumes of ethylene and 0.5 volume of carbon dioxide have been added.

Although in using ether to which an excess of anæsthetic gas has been added considerable of these gases will escape, I have found that enough of the gases remain at ordinary temperatures to bring about the desired effect of increasing the anæsthetic power of the ether.

When the ether which it is desired to use in preparing the new anaesthetic contains various substances such as alcohols, ketones, or aldehydes (which are usually present in the commercial product) in such proportions as to cause undesirable physiological reactions, the ether is carefully purified to remove these substances before saturating the ether with ethylene or carbon dioxide. Of course any substances ordinarily present in the ether which is not harmful may be permitted to form part of the final product which is to be used as an anaesthetic. The resulting anaesthetic is a mixture comprising ether and an anaesthetic gas and substantially free from substances capable of producing undesirable physiological effects.

The amount of ethylene or carbon dioxide in the ether being under control, it is possible to provide ether mixtures which contain definite and known amounts of anaesthetic gas or gases, so that the differing requirements of individual cases may be readily met; this control of the anaesthetic gas content is also advantageous in that it enables medical practitioners to obtain a product which will have a uniformly high anaesthetic power.

In some cases it may be found desirable to mix the anaesthetic gas with the ether in vapor form instead of absorbing the gas in the liquid ether; both methods are equally within the scope of my invention. Also in place of ethyl ether some other highly volatile narcotic or mixture of narcotics may be used, as for example a mixture containing ethyl alcohol, dimethyl ether, methyl-ethyl ether or methyl-propyl ether; these other narcotics, however, do not appear to present any advantages over the ethyl ether. Anaesthesia and analgesia seem to be best brought about by the joint action of the

highly volatile narcotic and the anaesthetic gas.

Although I have described my invention in considerable detail, and mentioned the use of an anaesthetic gas amounting to 1 to 6 times the volume of liquid ether with which it is to be associated, it will be understood that various changes may be made without departing from the scope of my invention, and that the proportion of anaesthetic gas may be varied to suit different conditions.

I claim:

1. A new composition of matter comprising ethyl ether charged with ethylene and being substantially free from substances having a tendency to produce undesirable physiological effects.

2. An anaesthetic comprising one volume of ethyl ether having from 1 to $3\frac{1}{2}$ volumes of ethylene gas absorbed therein.

3. An anaesthetic comprising one volume of ethyl ether containing ethylene and about $\frac{1}{2}$ volume of carbon dioxide, and being free from aldehydes and other substances capable of producing undesirable physiological effects.

4. An anaesthetic comprising one volume of ethyl ether containing from 1 to 3.5 volumes of ethylene and about 0.5 volume of carbon dioxide and being free from aldehydes and other substances capable of producing undesirable physiological effects.

5. An anaesthetic comprising one volume of liquid ethyl ether charged with carbon dioxide and with about 2 volumes of ethylene.

In testimony that I claim the foregoing I have hereunto set my hand.

JAMES HENRY COTTON.
